UNITED STATES PATENT OFFICE.

ARNOLD J. PETERSEN, OF CEDAR RAPIDS, IOWA.

LIGHT-BOWL HANGER.

1,338,958.

Specification of Letters Patent.

Patented May 4, 1920.

Application filed September 19, 1918. Serial No. 254,746.

To all whom it may concern:

Be it known that I, ARNOLD J. PETERSEN, a citizen of the United States, residing at Cedar Rapids, in the county of Linn and 5 State of Iowa, have invented certain new and useful Improvements in Light - Bowl Hangers; and I do hereby declare the following to be a full, clear, and exact description of the invention, such as will enable 10 others skilled in the art to which it appertains to make and use the same.

This invention relates to lighting fixtures, chiefly electrical, and has for its object to provide a simple, inexpensive and convenient 15 hanger for electrolier shades and reflectors.

The device is designed more especially for use in connection with the "semi-indirect" system of lighting, in which a large, shallow 20 bowl is hung under the lamps, but is not limited thereto, and may be applied to various types of lighting fixtures, as will hereafter more fully appear.

In the accompanying drawings, forming 25 a part of this specification, Figure 1 is a side elevation of my improved hanger, the depending bowl and the canopy being shown in section. Fig. 2 is a plan view of the hanger, with two lamps attached. Fig. 3 is a section in the line 3—3 of a slightly 30 modified form of hanger attached to a single lamp socket. Fig. 4 is a fragmentary plan view of the central spider shown in Fig. 3, as seen from the under side, and before the bending up of the screw-lugs. Fig. 35 5 is a fragmentary, sectional view of the type of hanger shown in Fig. 1, but inverted, with an attached arm adapted to support a side lamp.

40 In the drawings, the numeral 5 denotes a lamp-shade or bowl, having a constricted rim 6 forming a bead to engage the arms of the hanger to be described presently. This, with the lamps, is usually suspended 45 from the ceiling of the room, as by a tube 7, through which the conducting wires are run. The portion of tube immediately over the hanger is inclosed in an ornamental bell or canopy 8.

50 The hanger comprises a number of parts, and is described as follows:

A central spider 9 is stamped from sheet metal, with a central hole 10 for the passage of wires, and for connection with the means 55 of suspension. The hole may be small, as in Fig. 2, if the spider is to connect with a

tube simply, or enlarged, as shown in Fig. 4, if to be suspended by chains, or attached to a lamp-socket depending from a drop-cord, or the like. In the latter case a number of lugs 11, preferably three, are formed, and when struck up as shown in Fig. 3, serve for convenient attachment by screws 12 to the cover of a lamp-socket 13, as shown. From the sides of the central portion of the 60 spider project a number of arms, preferably three, indicated by the reference numeral 14, and an equal number of intermediate arms 15. The central part or hub of the spider is cupped, as shown, to give it stiffness, the cupping extending into the arms 65 14, which for a portion of their length are folded closely together, as shown at 16. The folded portion is pierced at 17 to receive a pin 18. The other arms 15 are left flat, and 70 provided with terminal holes 19, for the attachment of lamp-sockets as shown. These arms are easily bent and twisted to any desired position, so that the lamps may be set at any required angle, according to the 75 shape of the bowl, or otherwise.

Supplemental to the spider are extensions 20, formed of folded sheet metal fitting neatly over the folded parts of the spider. These are pierced with a series of holes, and 80 through one of them each arm may connect with an arm of the spider by a fastening pin. To any of the other holes may connect a terminal finger 21, similarly formed of sheet metal, but with one end formed as 85 a hinge 22, so that when attached to the extension 20 it may tilt in one direction as indicated by the dotted lines in Fig. 1. The finger is, however, provided with two holes, so that a pair of pins will fasten it rigidly 90 to the extension, when desired. The series of holes permits adjustment in the length of the radial arms through a wide range in 95 the sizes of bowls.

When the hanger is used for suspending 100 a bowl, as in Fig. 1, all the fingers may be attached by single pins, or one or two may be made rigid by the use of two pins. In either case the bowl is easily and quickly attached, by simply lifting it to position, 105 the hinged finger tilting upward until its tip passes the bead of the bowl, when it drops to holding position. To detach the bowl the hinged finger is lifted, and the operation reversed.

110 The hanger may be used as a shade support for a stand-lamp, the same side up as

in Fig. 1, with one or more hinged fingers, or either side up by making all the fingers rigid.

In Fig. 5 is shown a simple method of applying radial pendants for the support of side lights outside the bowl. A wire pendant 23, bent at 24 to form a hook, and looped at 25, slips into the channel of the extension 20, when set with the open side up, and is there held in place by a pair of pins 26.

The device provides a very simple and inexpensive hanger, adaptable to a variety of uses, and for various sizes of fixtures. Its construction is such that all parts are concealed, when in use, and there is practically nothing above the lamps to cast shadows on the ceiling.

Having thus described my invention, I claim:

1. A light-bowl hanger, comprising a central spider having radial arms terminating in flat, vertically disposed portions; folded extensions fitting thereover, folded terminal fingers fitting over the extensions, and means for attaching the extensions to the spider, and the fingers to the extensions.

2. A light-bowl hanger formed of sheet metal, with radial arms terminating outwardly in flat, vertically disposed portions by folding closely together, folded sheet-metal extensions fitting thereover, and fold-

ed fingers fitting over the extensions, and means for connecting the extensions rigidly to the spider, and the fingers hingedly to the extensions.

3. In a light-bowl hanger, a spider formed of sheet metal, and having radial arms terminating in flat, closely folded portions adapted to connect with extensions, and intermediate, flat arms with terminal holes, to serve as lamp supports.

4. A light-bowl hanger, comprising a central spider having flat, radial, perforated arms to serve as lamp-supports, and intermediate radial arms, closely folded at the ends, and the folded portion perforated, folded extensions fitting said arms, and provided with a series of perforations, and folded terminal fingers fitting over the extensions, and perforated for connection therewith, and adjustable lengthwise thereof.

5. A spider for light-bowl hangers, formed of sheet metal, with radial, bowl-supporting arms formed by folding the sides of the arms together, and having a central hole with up-struck, screw-holding lugs adjacent thereto.

In testimony whereof I affix my signature in presence of two witnesses.

ARNOLD J. PETERSEN.
